UNITED STATES PATENT OFFICE.

HARRY R. MENESEE, OF GLEN RIDGE, NEW JERSEY, ASSIGNOR TO WESTERN ELECTRIC COMPANY, INCORPORATED, OF NEW YORK, N. Y., A CORPORATION OF NEW YORK.

TEST DEVICE.

Application filed December 6, 1920. Serial No. 428,545.

To all whom it may concern:

Be it known that I, HARRY R. MENESEE, a citizen of the United States, residing at Glen Ridge, in the county of Essex, State 5 of New Jersey, have invented certain new and useful Improvements in Test Devices, of which the following is a full, clear, concise, and exact description.

This invention relates in general to test 10 devices, and more particularly to that type of test device generally referred to as service observing plugs.

It is customary to provide in the terminal room of a telephone exchange a connecting device, carried on the end of a flexible conducting cord, for temporarily connecting said cord to an exposed part of the line, the other end of the cord being connected, for example, to a service observing 20 operator's desk. By the provision of such a device, the service on a line may be tested by temporarily connecting the operator's equipment to the desired line.

It is one object of the invention to provide 25 a testing device, simple in construction, reliable in operation, and which can be easily and quickly adjusted for use.

In accordance with the present invention there is provided a test plug in which a 30 plurality of spring-pressed plunger contacts are adapted to engage a front strip, and a plunger actuated by a positive locking cam is adapted to engage the back strip, of the usual terminal block, thus holding the plug 35 in position for use.

The invention will be better understood from a consideration of the following description taken in combination with the accompanying drawing and the appended 40 claims.

Fig. 1 is a view in perspective showing a test device embodying the features of the present invention attached to the strips of a terminal block; and Fig. 2 is a detail view showing the enclosed spring-pressed contacts, and the method of connecting the flexible conducting cords thereto, certain parts being broken away for the sake of clearness.

50 Referring first to Fig. 1, the test clamp comprises a frame or plate 1 carrying on one end a plate or jaw 2, mounting a plurality of spring pressed plunger contacts 3, and enclosed in a micarta shell 4. On 55 the other end is mounted a plate or jaw

5 carrying the plunger 6 and the cam 7 adapted to rock on a pin 8 as a bearing, and held in engagement with the plunger 6 by means of the spring 9. Plunger 6 is adapted to slide in a slot formed in the 60 plate or jaw 5 and is firmly held in any desired position in the said slot by means of the pressure exerted by the positive locking cam or dog 7. Thus, the plunger 6 may readily be pressed forward to engage 65 any under strip 10 of the terminal block 11, but is held by means of the cam 7 against any pressure tending to release the plug from its hold on the said terminal strips. Upon applying pressure to the cam 7, however, the said cam releases its grip on the plunger 6, and the clamp may be readily removed from operative engagement with the terminal strips 10.

As is shown in Fig. 2, the contacts 3 are 70 mounted on the plate 2 and are suitably insulated therefrom by means of insulating strips 12. Each contact plunger 3 is provided with a spring 13 by means of which the said contacts are held securely in engagement with the ends of the corresponding terminal strips 10. Flexible conducting cords are adjusted to corresponding binding screws 14 before the plug is assembled. The micarta casing 4 is readily 75 removable and is provided as a protection to the spring pressed contacts 3.

A feature of the invention is the ease with which the plug may be adjusted to an operable position. The contacts 3 are placed 80 in engagement with the four terminal strips 10 to which the tip, ring, relay and line lamp conductors, respectively of a given line are usually connected. The plunger 6 is 85 simply pressed into engagement with the opposite end of any of these terminal strips and the plug is in a position for use. Upon pressing the cam 7 lightly with the finger, the plunger 6 releases its hold upon the terminal strip 10, and the clamp may be disengaged.

As a plug constructed in accordance with this invention does not depend upon the terminal support 11 as means for holding it in position, it is apparent that there is 90 no tendency to weaken the supporting structure by constant hard usage.

What is claimed is:

1. A test clamp comprising a frame, a plurality of spring-pressed plunger contacts 110

adapted to engage a front strip of a terminal block, an adjustable plunger slidably mounted in said frame and adapted to engage a back strip of a terminal block, and a 5 positive locking cam cooperating with said plunger to lock it in any set position holding the clamp in place on the terminal block.

2. A test clamp comprising a substantially C-shaped frame, a plurality of spring-10 pressed contacts mounted in one arm of said frame, and adapted to engage a front strip of a terminal block, a plunger slidably mounted in the opposite arm of said frame and adapted to engage a back strip of the 15 terminal block, a spring member disposed within said frame, and a cam held by said spring in engagement with said plunger to control the movement thereof.

3. A test clamp comprising a frame, a 20 block of insulating material arranged therein, contacts movable in said block, a bar

slidably arranged in said frame and disposed in line coaxially with respect to one of said contacts, and an automatically operated grip member for positively securing 25 said bar in adjusted position with reference to said contacts.

4. A test clamp comprising a frame, a removable block of insulating material securely arranged in said frame, spring 30 pressed contacts slidably arranged in said block, an adjustable member movable longitudinally in a plane common to the direction of movement of said contacts, and automatic means for restraining the movement 35 of said member against the action of said spring pressed contacts.

In witness whereof, I hereunto subscribe my name this 30th day of November A. D., 1920.

HARRY R. MENEFEE.
